UNITED STATES PATENT OFFICE.

HENRY T. BRODEN, OF BROOKLYN, ASSIGNOR TO THE STANDARD CUT
GLASS COMPANY, OF NEW YORK, N. Y.

DESIGN FOR A GLASS DISH.

SPECIFICATION forming part of Design No. 24,959, dated December 10, 1895.

Application filed October 9, 1895. Serial No. 565,192. Term of patent 7 years.

To all whom it may concern:

Be it known that I, HENRY T. BRODEN, a citizen of the United States, residing at Brooklyn, in the county of Kings and State of New York, have invented and produced a new and original Design for a Glass Dish, of which the following is a specification, reference being had to the accompanying drawings, forming a part thereof, in which—

Figure 1 is a plan view of a vessel embodying the features of the design, and Fig. 2 is a transverse section taken substantially on the line 2 2 of Fig. 1.

The design is applicable to any kind of glass dishes, such as bowls, plates, and jugs.

The design consists of a series of oval prisms A, crossing one another at different

angles, the contracted portions of the ovals being stopped short of the margin of the vessel. Within the center of the group of oval prisms a star prism B is formed, and from each point of the star a loop prism C is carried outward practically to the margin of the dish. The loop prisms receive within them the contracted portion of the oval prisms and cross the side lines of the wider portions of adjacent oval prisms.

I claim—

The design for a glass dish herein shown and described.

HENRY T. BRODEN.
